UNITED STATES PATENT OFFICE.

RALPH S. BARDWELL, OF LOS ANGELES, CALIFORNIA, ASSIGNOR TO SOLAR LIGHTING FIXTURE CO., OF LOS ANGELES, CALIFORNIA, A CORPORATION OF CALIFORNIA.

DESIGN FOR A BRACKET LANTERN.

Application filed November 1, 1927. Serial No. 23,967. Term of patent 3½ years.

To all whom it may concern:

Be it known that I, RALPH S. BARDWELL, a citizen of the United States, residing at Los Angeles, in the county of Los Angeles and State of California, have invented a new, original, and ornamental Design for a Bracket Lantern, of which the following is a specification, reference being had to the accompanying drawing, forming part thereof.

Figure 1 is a side view of a bracket lantern, showing my new design.

Figure 2 is a fragmentary detail showing

of the spike of the bracket lantern shown in Figure 1.

Figure 3 is a fragmentary detail showing of the loop of the bracket lantern shown in Figure 1.

Figure 4 is a fragmentary detail showing of the back of the bracket lantern shown in Figure 1.

I claim:

The ornamental design for a bracket lantern as shown.

RALPH S. BARDWELL.
